Primary Examiner — Mehri F Bajoul(74) *Attorney, Agent, or Firm* — Knobbe, Martens, Olson & Bear, LLP(57) **CLAIM**

The ornamental design for a remote control as shown and described.

DESCRIPTION

FIG. 1 is a front, top, and right side perspective view of a remote control embodying my new design.

FIG. 2 is a front view thereof.

FIG. 3 is a back view thereof.

FIG. 4 is a left side view thereof.

FIG. 5 is a right side view thereof.

FIG. 6 is a top view thereof; and,

FIG. 7 is a bottom view thereof.

Broken lines are used to illustrate features of the remote control which form no part of the claimed design.

1 Claim, 7 Drawing Sheets# US D1,051,990 S
